UNITED STATES PATENT OFFICE.

JAMES ELLWOOD JONES, OF SWITCHBACK, WEST VIRGINIA.

MECHANISM FOR DISCHARGING COKE-OVENS.

SPECIFICATION forming part of Letters Patent No. 731,912, dated June 23, 1903.
Application filed April 28, 1903. Serial No. 154,700. (No model.)

To all whom it may concern:

Be it known that I, JAMES ELLWOOD JONES, a citizen of the United States of America, residing at Switchback, in the county of McDowell, in the State of West Virginia, have invented certain new and useful Improvements in Mechanism for Discharging Coke-Ovens, of which the following is a specification.

This invention relates to a machine for pulling coke from coke-ovens, and is particularly adapted for discharging beehive ovens. In the manufacture of metallurgical coke the oven known as the "beehive" oven, so called because of its dome-shaped form, has been generally adopted, being found to give the best results. In the burning of the coal the coke is produced in the form of a caked mass having a vertical stratification, and it is desirable to avoid as much as possible horizontal breakage of the sticks and lumps extracted from the oven.

The object of this invention is to secure a quick and thorough discharge of the oven without unnecessary breakage of the coke.

25 The invention consists principally in coke-puller comprising an underworking beveled scraper, which will slide along the bottom of a coke-oven and loosen the coke above it on the instroke, and an overworking claw 30 coöoperating with said scraper to grasp and withdraw the loosened coke on the outstroke.

Figure 1 represents a side elevation of one embodiment of this coke-puller, a section of a portion of the coke-oven and of the receiving-car. Fig. 2 represents, on an enlarged scale, a vertical section on line 2 2 of Fig. 1, showing the mechanism for actuating the bars to operate the coke-puller. Fig. 3 represents a front view of the mechanism for actuating and timing the bar which controls the grasping-claw. Fig. 4 represents a plan view thereof on line 4 4 of Fig. 3. Fig. 5 represents a vertical transverse section on line 5 5 of Figs. 3 and 4, showing a lever for connecting and disconnecting said mechanism. Fig. 6 represents a broken plan view, on an enlarged scale, of the actuating-bars of the coke-puller and a lever, partly in section, for actuating the release-bar. Fig. 7 represents a vertical section on line 7 7 of Fig. 6. Fig. 8 represents a vertical section on line 8 8 of

Fig. 6, showing the automatic catch for the claw-actuating bar.

The same reference characters indicate corresponding parts in the different figures.

This coke-pulling apparatus may be used 55 for discharging various forms of coke-ovens.

The drawings represent fragments of a beehive coke-oven 10, provided, as usual, with a top opening, which serves for a feed and blast opening, and with a lateral discharge-opening 12. These openings are closed and sealed in the usual manner during the coking operation or a part thereof. A number of such coke-ovens are arranged side 60 by side, and a railway-track 20 is disposed in front thereof, on which travel the coke-cars 30 for receiving and conveying away the coke from the oven. Any suitable means may be employed for disposing of the coke withdrawn 65 from the ovens. A track 40 is disposed outside the track 20 parallel therewith, and a machine-car 50, on which the discharging apparatus is mounted, travels on said track 40. 70

A suitable frame for supporting the mechanism of the coke-puller proper is mounted 75 on the car 50. This frame may comprise two standards, as 51, secured to the platform of the car at opposite ends thereof and properly connected by a top cross-bar 53 and intermediate cross-bars 54 and 55. The cross-bar 53

is provided with a vertical shaft-bearing 56, and the car-platform is provided in line therewith with a vertical shaft-bearing 57, having an exterior flange 58, adapted to serve as a step-bearing. The platform of the machine-car is also provided with standards, as 60, on one side and with standards, as 62, on the other side thereof. These standards are connected on one side by two pairs of elongated antifriction-rollers 64 and 65 and 66 and 67, disposed one above the other in a horizontal plane midway of the height of the main frame, and these rolls form guideways for the coke-puller, as hereinafter described. Corresponding rollers 64' and 65' and 66' and 67' connect the standards at the other side of the car and form guides for said coke-puller.

A horizontal driving-shaft 70 is supported in bearings at the upper end of the frame and provided with a fly-wheel 72 and a beveled pinion 73. Any suitable engine or motor

may be employed for imparting motion to the driving-shaft, and this engine is provided with any suitable means usually employed for quickly starting, stopping, and reversing.

5 A vertical shaft 90 is disposed in the vertical bearings 56 and 57 and provided at its upper end with a beveled gear-wheel 91, which meshes with the beveled pinion 73 on the driving-shaft 70. This shaft is provided with a fixed pinion 92 and with a loose pinion 93, the hubs of which have clutch-faces. A sliding clutch 94, splined to the shaft, is adapted to engage the loose pinion 93 and lock it to the shaft, and a loose clutch 95 is adapted to engage the fixed pinion 92 and be turned thereby in unison with the shaft. These clutches are respectively actuated by clutch-levers 96 and 97. The clutch 95 is provided on the end opposite its clutch-face with a notch 98 for the purpose hereinafter described. The shaft 90, which may extend through the platform, is shown as broken off; but it may be connected by suitable clutch-gearing with one of the car-axles and utilized to drive the car along the track.

A swiveling carriage is mounted on the machine-car for carrying the coke-puller, which is thrust into and retracted from the oven in the pulling of coke therefrom and moved laterally by means of the swiveling carriage to engage the coke at the side of the oven. This swiveling carriage may be of any suitable construction. As herein shown, it comprises a sleeve 100, surrounding the vertical shaft 90 and resting on the step-bearing 58, being provided at its lower end with a worm-wheel 101. A bracket 102 extends upward from this sleeve and supports two horizontal guideways 103 and 104 at one side of the shaft. The guide 103 is disposed opposite the loose pinion 93 and is open at the side adjacent to said pinion. The bottom of these guideways may be provided with antifriction-rolls, as 105. The guideway 104 is also open on its side adjacent to the shaft. A horizontal shaft 110 is journaled in bearings 111 and 112 on the car-body and provided with a worm 113, which engages the worm-wheel 101, and with a hand-crank 114, whereby the swiveling carriage may be turned to give a lateral thrust to the coke-puller.

A coke-puller comprising an underworking scraper and an overworking grappling-claw is mounted on and actuated from the swiveling carriage. The scraper is adapted to slide along the bottom of the oven underneath the bed of coke and is provided with means to lift and separate a portion thereof from the caked mass of coke within the oven on its in-stroke and to pull or assist in pulling the so loosened coke out of the oven on its outstroke. This double-acting scraper, which lifts and breaks the coke on the instroke and pulls or scrapes it out on the outstroke, may be constructed in any suitable form which adapts it to its functions. The scraper shown in the drawings is attached to a sliding bar 140,

disposed in the lower guideway 103 of the swiveling carriage and passing between the rolls 64 and 65 on one side and between the rolls 64' and 65' on the other. This bar is provided along its rear portion with vertical rack-teeth 141, which engage the lower pinion 93 on the vertical shaft 90. The bar has a beveled outer end 142, which is provided on its under side with an antifriction-roller 143 to facilitate its movement on the oven-bottom. The scraper proper is composed of a flat cross-plate 144, disposed at the outer end of said bar, and a bow-shaped plate 145, secured at its center to the beveled end 142 and at its ends to the ends of said cross-plate 144. The plate 145 thus forms a bevel or wedge inclined upward and backward from its outer edge. Both plates 144 and 145 are preferably arc-shaped at their outer edges to correspond with the shape of the oven, so that they may operate close to the wall thereof.

The overworking grappling-claw which operates in conjunction with the scraper comprises a bent shank 150, pivoted at its lower rear end to the bar 140 of the scraper, and a claw-head 151, secured to the outer end of said shank. The claw is preferably a comb-like or toothed structure and shaped to conform to the scraper. Means are provided for raising the claw to escape the coke on the in-stroke of the coke-puller and to prepare it for grasping the coke at the completion of the in-stroke. The means shown for this purpose comprise a bar 160, disposed in the upper guideway 104 and between the rolls 66 and 67 and 66' and 67' and provided with vertical rack-teeth 161 along its rear part. The outer end of this bar is connected to the shank 150 of the grappling-claw. Any suitable means are provided for operating this bar independently of the movement of the bar 140, and they preferably include devices for automatically determining the backward stroke of the bar 160, so that it will move just far enough to properly raise or open the claw. A bracket 104' is mounted on the upper guideway 104, and a short vertical shaft 106 is supported in said guideway and bracket. This shaft has a loose pinion 107, which meshes with the fixed pinion 92 on the vertical shaft 90, a fixed pinion 108, which meshes with the bar 160, and a splined clutch 109, adapted to engage said loose pinion for locking the shaft 106 to move in unison therewith. A yoke 98', sliding in a slotted box 99 on the guideway 104, connects the loose clutch 95 on the shaft 90 with the splined clutch 109 on the shaft 106. The lever 97 is pivoted on a lateral bracket 171 on said guideway and engages said yoke, whereby the latter may be lifted to throw the clutch 109 into engagement with the pinion 107 to cause the rotation of the shaft 106 and the movement of the bar 160. A fixed tooth 172 on the guideway engages the notch 98 in the clutch 95 when the yoke is depressed, and a spring 173 operates to depress the yoke when the notch

registers with the tooth. When the yoke is raised, the clutch 95 is lifted out of engagement with the tooth 172 and into engagement with the fixed pinion 92 and rides for one rotation on the upper end of said tooth. When the clutch completes a turn, the bar 160 is drawn back sufficiently to open the claw and the notch 98 comes opposite the tooth and a spring 173 depresses the yoke and disengages the clutch from the pinion 92. These devices thus act as an automatic stop for the retraction of the bar.

Means are provided for holding the claw in open position. The means shown comprise a spring-latch 162, pivoted on the bar 160, and a dog 147, pivoted on a bracket 146, mounted on the bar 140 and adapted to project through a slot in the top of said bracket. When the bar 160 is retracted a sufficient distance relative to the bar 140 to open the claw 151, the latch acts automatically to engage the dog and hold the claw in open position.

Means are provided whereby the operator may release the latch 162 to permit the closing of the claw. The means shown for this purpose comprise a slide-rod 190, connected at its outer end to the dog 147, and means for actuating said slide-rod. The actuating means may comprise a grip-lever 200, pivoted to a bracket 201, attached to the swiveling carriage. The inner end of this grip-lever is provided with an eye 202, through which the slide-rod 190 passes, and with a grip-dog 203, adapted to bite said rod. A rod 204 connects the grip-dog with a finger-lever 205 at the outer end of the lever 200. A spring 206 tends to hold the lever in the position shown in Fig. 6, and stops 207 and 208 on the guide 40 limit the throw of said lever in either direction. When the operator grasps the lever 200, he closes the finger-lever 205 and causes the dog 203 to bite the release-rod 190 and at the same time swings the lever toward the left, whereby the rod is pulled backward and the dog 147 swung below the top of the standard 146 out of engagement with the latch 162. A stud 165 on the latch 162 holds it out of the slot through which the dog works. A spring 163, connected at one end to the bracket 146 and at the other end to the bar 160, serves as an automatic closer for the claw when the bar 160 is released.

In the use of this machine when the coke-oven is ready to be drawn the coke-car 30 is moved into position opposite the oven-opening and the machine-car 50 is also adjusted opposite the oven-opening on the outside track, as shown in Fig. 1. The swiveling carriage 100 is adjusted by the hand-wheel 114 to bring the guideways 103 and 104 at right angles with the track, so as to make the first thrust of the coke-puller in a direct line into the oven. The vertical shaft 90 is driven by the motor in the direction of the arrow *a* in Fig. 1, and by the lever 96 the clutch 94 is brought into position to lock the pinion 93 in unison with said shaft.

This will cause a forward thrust of the bar 140, and the coke-puller at the end thereof will enter the oven a distance sufficient to 70 make a proper drawing of the coke. On this instroke of the coke-puller the beveled or wedge-shaped scraper will lift and break or loosen from the caked mass in the oven a body of coke equal in width to the width of 75 the scraper and of a length equal to the length of the instroke. Several thrusts are to be made on each side at different angles in discharging the oven. During the instroke and after the claw 150 has passed the door-opening 80 the hand-lever 97 is depressed by the operator and the clutches 95 and 109 placed in position to transmit motion from the fixed pinion 92 on the vertical shaft 90 to the shaft 106, which carries the pinion 108, whereby 85 the bar 160 is drawn backward and the grappling-claw 150 raised over the bed of coke and automatically locked in open position and the clutch-gearing automatically disengaged by the means before described or any 90 equivalent means. When the coke-puller has entered the oven a distance sufficient to make a proper drawing of coke, the operator swings the lever 96, and thereby unclutches the driving-pinion 93, whereby the inward 95 motion of the coke-puller is stopped. The locking device for the grappling-claw is then released and the spring 163 operates to close the claw 150 in front of the loosened coke. The claw may be repeatedly opened and 100 closed if found necessary to get a good hold on the coke. Then the operator will reverse the engine or otherwise cause the shaft 90 to rotate in the direction of the arrow *b* in Fig. 1 and again clutch the pinion 93 to said shaft. 105 This will cause a withdrawing from the oven of the coke-puller, and the mass of loosened coke will be drawn through the door 12 and allowed to fall into the coke-car 30. The claw 150 prevents any coke from falling back 110 over the scraper and being left in the oven. After this stroke of the coke-puller another may be made in the same line, the puller being pushed farther into the oven, so as to take up another load back to the opposite 115 wall of the oven. Then the hand-wheel 114 will be successively manipulated to swing the swiveling frame into position to make lateral thrusts into the oven on opposite sides thereof, the several parts being manipulated, as 120 before described, to effect the coke-pulling stroke. The spring 163 may be omitted and the claw operated solely by the mechanism controlled by the operator, if desired.

I claim as my invention—

1. In a coke-puller the combination of an underworking scraper movable over the bottom of a coke-oven and provided with means for loosening the mass of coke under which it passes on the instroke from the caked mass 130 of coke within the oven, and an overworking claw connected therewith and adapted to close over said scraper for grasping the loosened coke on the outstroke.

2. In a coke-puller the combination of an underworking scraper movable over the bottom of a coke-oven and provided with a lifting-surface for loosening the mass of coke under which it passes on the instroke from the caked mass of coke within the oven, and an overworking claw connected therewith and adapted to close over said scraper for grasping the loosened coke on the outstroke.
3. In a coke-puller the combination of an underworking scraper movable over the bottom of a coke-oven and provided with a beveled front face for loosening the mass of coke under which it passes on the instroke from the caked mass of coke within the oven, and an overworking claw connected therewith and adapted to close over said scraper for grasping the loosened coke on the outstroke.
4. In a coke-puller the combination of an underworking scraper movable over the bottom of a coke-oven and provided with means for loosening the mass of coke under which it passes on the instroke from the caked mass of coke within the oven, an overworking claw connected therewith and adapted to close over said scraper for grasping loosened coke on the outstroke, and means for opening and closing said claw.
5. In a coke-puller the combination of an underworking scraper movable over the bottom of a coke-oven and provided with means for loosening the mass of coke under which it passes on the instroke from the caked mass of coke within the oven, an overworking claw connected therewith and adapted to close over said scraper for grasping the loosened coke on the outstroke, means for opening said claw, and automatic means for closing it.
6. In a coke-puller the combination of an underworking scraper movable over the bottom of a coke-oven and provided with means for loosening the mass of coke under which it passes on the instroke from the caked mass of coke within the oven, an overworking claw having a bent shank hinged to the shank of said scraper and operating to close over said scraper for grasping the loosened coke on the outstroke, a bar connected with said claw, and means for reciprocating said bar to open and close the claw.
7. In an apparatus for discharging coke-ovens, the combination of a coke-puller comprising an underworking scraper and an overworking claw connected therewith, means for thrusting and retracting said coke-puller into and out of a coke-oven, and means for opening and closing said claw.
8. The combination of a wheeled vehicle, a swiveling carriage mounted thereon, a vertical shaft mounted on said vehicle and provided with pinions, bars supported on said swiveling carriage and provided with racks engaging said pinions, intermediate clutch mechanisms for connecting said pinions with said shaft, a scraper attached to the lower bar and a grappling-claw connected with the upper bar.
9. In an apparatus for discharging coke-ovens, the combination of a coke-puller comprising an underworking scraper and an overworking claw connected therewith, means for thrusting and retracting said coke-puller into and out of a coke-oven, means for opening and closing said claw, and means for automatically controlling the opening mechanism.
10. In an apparatus for discharging coke-ovens, the combination of a coke-puller comprising an underworking scraper and an overworking claw connected therewith, means for thrusting and retracting said coke-puller into and out of a coke-oven, means for opening and closing said claw and means for locking said claw in open position.
11. In an apparatus for discharging coke-ovens, the combination of a coke-puller comprising an underworking scraper and an overworking claw connected therewith, means for thrusting and retracting said coke-puller into and out of a coke-oven, means for opening and closing said claw and an automatic lock for holding said claw in open position.
12. In an apparatus for discharging coke-ovens, the combination of a coke-puller comprising an underworking scraper and an overworking claw connected therewith, means for thrusting and retracting said coke-puller into and out of a coke-oven, means for opening and closing said claw, an automatic lock for holding said claw in open position and means accessible to the operator for releasing said lock.

JAS. ELLWOOD JONES.
